UNITED STATES PATENT OFFICE.

LUTHER M. WALKER, OF AFTON, IOWA.

GRAIN-VALVE.

SPECIFICATION forming part of Letters Patent No. 624,712, dated May 9, 1899.

Application filed June 18, 1898. Serial No. 683,838. (No model.)

To all whom it may concern:

Be it known that I, LUTHER M. WALKER, of Afton, in the county of Union, State of Iowa, have invented certain new and useful 5 Improvements in Grain-Valves, of which the following is a complete specification, reference being had to the accompanying drawings.

The object of my invention is to produce 10 an improved grain-valve mechanism comprising a frame adapted to be secured to a blank wall—as, for example, that of a grain-car—or to a door of a grain-car. The frame of my valve mechanism is so constructed as to 15 be readily applicable to such a wall and to afford for such wall when applied thereto ample resistance to the strain imposed by the weight of grain contained within the car or receptacle of which said wall constitutes a 20 part. The valve mechanism also comprehends means for opening or closing the valve from the outside of the car or receptacle.

Grain-cars or similar receptacles out of necessity are built of planks or boards firmly 25 united together by the framework of the structure. In applying a valve it is necessary to cut through the wall, and thereby weaken it. My invention therefore includes means of sustaining the wall after an opening 30 is made in it and includes special provision for facilitating the manipulation of the valve. Both the securing of the frame to the wall and the means adapted for manipulating the valve have special regard not only to the 35 great weight which the valve has to sustain in use, but also to the resistance opposed by the weight of grain to the operation of the valve.

In the accompanying drawings, Figure I is 40 a side elevation of a portion of a car-body, showing a grain-door equipped with my valve mechanism, the elevated or open position of the valve being shown in dotted lines. Fig. II is a rear elevation of a portion of a grain-door, showing my valve mechanism applied thereto, the valve being closed. Fig. III is a section on the line III III of Fig. I. Fig. IV is a section on the line IV IV of Fig. II.

Referring to the numerals on the drawings, 45 1 indicates a portion of a car-body representing, by way of example, a receptacle to which my device is applicable.

2 indicates the usual doorway, which is illustrated as closed by an ordinary grain-door 3, which represents a wall to which my valve 55 mechanism is directly applied.

4 indicates an opening formed in the door 3 near its bottom for the accommodation of my valve mechanism, the aperture being designed to permit the discharge of grain by its 60 own weight and being of any suitable shape and size, the oval form illustrated being preferred.

Around the edges of the opening 4 and conforming to its contour I provide what may be 65 termed "inside" and "outside" frame-plates 6 and 7. These plates are preferably made of heavy metal, and being connected by bolts 8, passing through them and through the material of the door 3, afford a rigid and unyielding support for the door around the aperture, such support being, as above suggested, essential in view of the fact that the door is 70 made of planks or boards which when cut away to form the aperture 4 require means of support independent of the original or ordinary structure.

Each of the frame-plates 6 and 7 is provided with an extension or tail piece 10, designed to afford rigid and durable bearings for a valve- 80 actuating shaft 11. To the inner end of the shaft 11 is firmly secured, as by an extension 12, a grain-valve 13. The valve, with its extension 12, corresponds in general contour to the frame-plate, against which it works. I 85 prefer to provide the inner frame-plate 6 with a projection or flange 14 and to provide the extension 12 of the valve with a shoulder 15, which fits and works against the flange 14 where those parts come into juxtaposition. 90 (See Fig. III.) Any suitable means of securing the valve to the shaft 11 may be employed—as, for example, a square end upon the shaft fitting a corresponding aperture in the extension 12 of the valve. Upon the outside of the wall or door 3 I provide means for 95 actuating the valve, which may consist simply of a lever 17, fixed to the outer end of the shaft 11 and working in a plane parallel with the face of the door. I prefer to provide as means of fixing the position of the lever 17 with respect to the wall a segmental 100 guide-rail 18, secured at its opposite ends to the door 3 and provided with notches 19 for

engaging the lever 17 and securing it in those positions in which the valve is completely opened or closed.

In valve mechanism for grain-cars or similar receptacles account must be taken of the great weight of grain within the car and the pressure exerted thereby against the valve. Such pressure tends not only to separate the valve-frame from the wall to which it is secured, but also to impede the manipulation of the valve. For this reason I prefer to employ a valve provided on that side which works against the valve-frame with a plane face and on the other side with a beveled face, which defines a structure having a comparatively thin edge and a heavy middle or body part. By the employment of this structure the movement of the valve is facilitated through the wedging action afforded by the beveled faces.

Upon the plate 6 I provide lugs 20, which constitute stop-pieces for limiting the closing movement of the valve.

Upon the outer frame-plate 7 I provide a series of chute-supporting lugs 21, adapted to receive the terminal flange of a grain-chute. Three lugs 21 may be employed, one on the lower part of the frame and the other two on opposite sides thereof. Above the bottom lug 21 I employ a latch 22, adapted to operate against a chute to secure it in place within the lugs 21.

What I claim is—

1. The combination with a frame - plate adapted to be secured around an aperture in the wall of a grain-receptacle, of an inwardly-extending flange around the aperture in the said plate, a valve working shearwise across the face of said flange, and valve-actuating mechanism, the parts above mentioned being adapted to permit the free movement of the valve through the material confined within the receptacle without crowding it against the wall to which the frame-plate is secured, substantially as set forth.

2. The combination with a pair of frame-

plates and means of uniting the plates together upon opposite sides of a blank wall around an aperture therein, of a flange upon the inner plate, a valve provided with a shouldered extension, the shoulder of the extension working against the flange and the valve proper working against the face of the plate, a shaft extending through the plates and secured to the shouldered extension of the valve, and a lever secured to the opposite extremity of said shaft, substantially as set forth.

3. The combination with a pair of frame-plates, and means for securing them together upon opposite sides of a blank wall around an aperture therein, of a valve working against the inner plate, valve-actuating mechanism extending beyond the outer plate, and chute-retaining lugs in the outer plate, substantially as set forth.

4. The combination with a frame - plate adapted to be secured around an aperture in the wall of a grain-receptacle, of a shaft working in bearings in said plate, a valve secured to the inner end of said shaft, a lever secured to the outer end thereof, and means for securing the lever in fixed position with respect to the wall of the receptacle, substantially as set forth.

5. The combination with a pair of plates, and means of uniting them upon opposite sides of a blank wall around an aperture therein, of a shaft working in bearings in said plates, a valve secured to one end of the shaft, a lever secured to the other end thereof, and a guard-rail adapted to be secured to the wall and provided with means for securing the lever in different fixed positions, substantially as set forth.

In testimony of all which I have hereunto subscribed my name.

LUTHER M. WALKER.
